UNITED STATES PATENT OFFICE.

RICHARD L. GEASLEN, OF CHICAGO, ILLINOIS.

WATER-HEATING APPARATUS.

Application filed May 31, 1927. Serial No. 195,246.

This invention relates to means for heating water for domestic or other purposes, more particularly to means of this kind immersed in a body of hot water, whereby the 5 heat of the body of hot water will be absorbed by the water in said heating means, thus making it possible to provide a domestic, hot-water supply by means of heat derived from the water of the hot-water or 10 steam-heating plant, or from the water in the boiler of a power plant.

Generally stated, the object of the invention is to provide a novel and improved construction for mounting the tubes in which 15 the water to be heated is circulated, whereby said tubes are immersed in the water of the boiler, or in the water of a tank containing hot water.

A special object is to provide a novel and 20 improved construction whereby the tubes containing the water to be heated can be easily and conveniently detached from the wall of the boiler or tank containing the hot water from which the heat is derived for 25 heating the water in the tubes, and for insuring tight joints which will prevent leakage of the water from the boiler or tank, as well as from said tubes.

It is also an object to provide certain 30 details and features of construction, and combinations tending to increase the general efficiency and the desirability of an auxiliary water-heating apparatus of this particular character.

To the foregoing and other useful ends, the invention consists in the matters herein-after set forth and claimed, and shown in the accompanying drawings, in which,—

Fig. 1 is a front elevation of a boiler and 40 furnace having an auxiliary, hot-water attachment involving the principles of the invention.

Fig. 2 is a side elevation of the structure shown in Fig. 1.

Fig. 3 is an enlarged, vertical, longitudinal section of the water-heating unit shown in Fig. 1, with certain portions of the water tubes broken away for convenience of illustration.

Fig. 4 is a vertical section on line 4—4 in Fig. 3.

Fig. 5 is a side elevation of a heating unit, showing another form of the invention.

Fig. 6 is a similar view, showing a different 55 form of the invention.

Fig. 7 is a view similar to Fig. 3, showing a different form of the invention, being a vertical section on line 7—7 in Fig. 8.

Fig. 8 is a vertical section on line 8—8 in Fig. 7.

Fig. 9 is a view similar to Fig. 2, showing a different form of the invention.

Fig. 10 is an enlarged, vertical, longitudinal section of the drum or tank in which the auxiliary, heating unit is inserted, shown in 65 Fig. 9, having certain portions broken away for convenience of illustration.

Fig. 11 is a view similar to the right-hand end portion of Fig. 10, showing a different form of the invention.

Fig. 12 is a cross section of a tube showing a different form of the invention.

As shown in Figs. 1 to 8, inclusive, the invention comprises a furnace and boiler 1 of any suitable or desired character, having an 75 auxiliary heating attachment comprising a heating unit 2 inserted through the front wall of the boiler and connected to circulate the heated water in the storage tank 3 of the auxiliary heating apparatus. The said unit, 80 as shown in Figs. 3 and 4, comprises a U-shaped pair of tubes 4 having the ends thereof tightly inserted in the openings 5 of the plate 6, and thereby rigidly and permanently united with said plate. The header of the 85 unit comprises a casting having the two chambers 7 and 8 having, respectively, the outlet and inlet pipes 9 and 10 disposed transversely thereof and in alignment with each other, as shown, the two pipes being 90 disposed vertically, as shown in the drawings. The header has a flange 11 provided with holes 12 for the bolts 13, which are preferably threaded and screwed into the front wall 14 of the boiler, as shown. These bolts or 95 threaded rods are provided with nuts 15, by which the plate 6 is clamped against the boiler front, and with nuts 16 which bear against the flange 11, and thereby draw the header into tight engagement with the plate 100 6, with gaskets or packing 17 between the edges of the header and the seat formed, as shown, in the face of the plate 6, thereby forming a tight joint to prevent leakage.

With this arrangement, water flows downward from the tank 3 through the pipe 18, through the pipe 10 into the chamber 8, then through the pipes 4 and into the chamber 7, then out through the pipe 9, and through the pipe 19 to said tank 3, thus circulating the 110

heated water absorbed from the body of hot water in the boiler into the water circulating through the pipes 4 of the auxiliary heating unit.

5 Fig. 5 shows a construction similar to that shown in Fig. 3, but in this case the tubes 20 are given a forty-five degree twist, as shown, thereby to facilitate the circulation of the water therein.

10 In Fig. 6 the construction is similar to that shown in Fig. 3, but in this case the tubes 21 provide a group of two bends for each of the chambers or compartments 7 and 8 of the header, so that water flows out of one 15 compartment or chamber through a plurality of tubes, and then back through a plurality of tubes into the other compartment or chamber.

In Figs. 7 and 8, the construction is similar to that shown in Fig. 3, but in this case there is also a difference in the arrangement of the tubes. In Figs. 7 and 8 the header and plate construction, held by bolts to the front of the boiler, are the same, and the 25 header has the two chambers 7 and 8 previously described, having the pipes 9 and 10 in communication therewith. In this case, however, the plate 22 is somewhat different from the plate 6, being provided with six 30 openings for six tube ends, as follows: Water enters the compartment 8 through the pipe 10, and flows out of this compartment through one leg of the U-shaped pair of tubes 23, and back through the other leg of 35 this pair of tubes into the passage 24 in said plate, and then out through one leg of the U-shaped pair of tubes 25, and back through the other leg into the passage 26 formed in said plate, and up through this passage into one leg of the pair of tubes 27, and then back 40 through the other leg of this pair into the compartment 7, as indicated by the arrows in Figs. 7 and 8 of the drawings. With this arrangement, the water is circulated back and forth six times, after leaving the header, 45 before it returns to the header, and with this longer period of circulation the water absorbs more heat from the body of water in the boiler, and is raised to a higher temperature.

50 As shown in Fig. 9, the invention is applied to a form of boiler 28 of such character that it will be impractical to insert the heating unit in the front of the boiler, and hence a tank 29 is mounted on the side of the boiler and provided with inlet and outlet connections 30 and 31, by which water from the boiler enters the tank, and then leaves the tank and flows back to the boiler, thus keeping a body of hot water within the tank.

The heating unit shown in Fig. 10 is inserted in the end of the tank 29, as shown, and this heating unit is substantially the same as the one shown in Fig. 6, or it may

be like the one shown in Fig. 3, or the one shown in Fig. 5, or the one shown in Fig. 7 of the drawings, having the header provided with the same two compartments 7 and 8, and having the pipes 21 shown in Fig. 6 of 70 the drawings. With this arrangement, the heat of the water in the tank 29 is absorbed by the water in the tubes 21, and hence the water which enters the header through the pipe 10 has its temperature raised considerably, and finally escapes from the header through the pipe 9, as previously explained.

75 In Fig. 11, the construction is similar to that shown at the right in Fig. 10, but in this case the tubes 32 of the heating unit terminate in a single compartment header 33, as shown, so that the water flowing through the different tubes from the compartment 8 is all mixed together when it enters the header 33, before traveling back through 80 the tubes which lead to the compartment 7, in a manner that will be readily understood.

85 In each form of the invention, it will be seen that the heating plate and header are provided with packing or gaskets between 90 them, like the packing or gaskets 17 shown in Fig. 3. This provides a tight joint to prevent leakage between the plate and the header, the plate being held tightly to the front of the boiler, or to the front of the tank containing water, and thereby preventing leakage of the water from the boiler or tank. In each case, also, only the removal of the outer nuts 16 is necessary to detach the 95 header from the boiler front, or from the tank structure, thus leaving the plate 6, in each case, fastened to the front of the boiler. The plate in this way forms a detachable seat, as it can be removed by taking off the nuts 15 after the removal of the header, but the seat provided by the plate does not need to be removed when the header is removed. When the header is removed, without removing the plate 6, in each form of the invention, the tubes remain held in place by 100 the plate, and leakage from the boiler does not occur, as the removal of the header alone does not cause any such leakage. But, if desired, after removing the header, the plate 6, in each form of the invention, can 105 be removed with its tubes 4, or with the tubes of any of the other forms of the invention, from the boiler, by removing the nuts 15 from the threaded bolts or rods 13, leaving the latter fixed firmly in the wall of 110 the boiler or tank. In other words, in each form of the invention, the header itself is separable from the remainder of the heating unit, leaving said remainder fixed on the boiler or tank, if desired, so that removal 115 of the header does not open up the boiler or tank, and does not create any leakage from the boiler or tank, and, of course, this involves, in the embodiment of the invention shown and described, attachment of the 120

plate and tubes portion of the unit to the boiler first, or to the tank first, thus, in any form of the invention, closing the opening in the wall of the boiler or tank; and then the header portion of the auxiliary heating unit is placed in position and secured by the tightening of the nuts 16, as shown and described.

As shown in Fig. 12 of the drawings, the tubes can be oval in cross section, if desired, thus increasing the effective surface of the tubes, while not increasing the width of the header. For example, in Fig. 3 of the drawings, the pipes 4 can be oval in cross section, without changing the relative proportions shown in Fig. 3, by locating the minor axes of the ovals in parallel planes, so that the broader sides of the tubes will be opposed to each other. This oval formation of the tubes, it will be seen, can be used in any of the different forms of the invention, or different forms of header, or arrangement of tubes, shown and described.

Without disclaiming anything, and without prejudice to any novelty disclosed, what I claim as my invention is:

1. In a heating apparatus unit, the combination of a support having an opening therein through which the heating unit is inserted, a plate accessibly secured to the outer side of said support and forming a seat at the outer side of said opening, tubes having their open end portions rigid with said plate and extending through said opening, the plate and tubes forming a closure for said opening, a header having compartments for incoming and outgoing fluid, with inlet and outlet means for said compartments, and securing means for accessibly and removably

holding said header on said seat, preventing removal of said plate except by first detaching said header therefrom, but permitting removal of the header alone while said plate and tubes remain in fixed position on said support and while said opening remains closed.

2. A structure as specified in claim 1, said securing means comprising threaded rods extending through portions of said header and plate and fixed at one end in said support, comprising nuts on said threaded rods to engage and hold the plate in position, comprising also nuts on said rods to engage and hold the header in position, said last mentioned nuts being removable from said rods without disturbing said first mentioned nuts.

3. A structure as specified in claim 1, having means in said seat forming a tight joint between said header and plate, preventing leakage from said compartments of the header, said support being the wall of a boiler or tank, and said plate preventing leakage from said boiler or tank after said header is removed.

4. A structure as specified in claim 1, said securing means comprising threaded rods fixed in said support, both the plate and the header being removable from said rods, leaving said rods fixed in said support.

5. A structure as specified in claim 1, said securing means comprising an upper rod and lower rod fixed in said support, and nuts on said rods to draw the header and plate tightly into position.

Specification signed this 29th day of March, 1927.

RICHARD L. GEASLEN.
